UNITED STATES PATENT OFFICE.

HENRY CHARLES QUINCY, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR A FORK OR ANALOGOUS ARTICLE.

44,112.

Specification for Design.

Patented May 27, 1913.

Application filed December 4, 1912. Serial No. 734,996. Term of patent 14 years.

To all whom it may concern:

Be it known that I, HENRY CHARLES QUINCY, a citizen of the United States, residing at Newburyport, in the county of Essex and Commonwealth of Massachusetts, have invented a new, original, and ornamental Design for Forks or Analogous Articles, of which the following is a specification, reference being had to the accompanying drawing, forming a part thereof.

In the accompanying drawing, my new and original design is embodied in a fork having a handle like the handle for spoons and analogous articles illustrated in Design Patent No. 42,633 of June 25, 1912, issued to Towle Manufacturing Company on an application of Edward Henry Colby, Figure 1 being a perspective view of the front of the fork, Fig. 2 an elevation of the back of the fork, and Fig. 3 an enlarged fragmentary perspective, illustrating the design in detail.

In my new design the fork tines each have six faces, as shown more particularly in Fig. 3, the two side faces *a*, *b*, being sub-

stantially flat, and the two front faces *c*, *d* and two rear faces *e*, *f*, being convexly curved laterally. The front tine faces *c*, *d*, meet at the center of the tine and form a more or less well defined line *g* extending longitudinally of the tine, and similarly for the rear faces *e*, *f*. At the inner end of each tine the convexly curved front and rear faces merge, without break, into the front and rear faces respectively of the plain base *h* of the tine body, as indicated by dotted lines in Figs. 1 and 2.

The depth of each tine along the lines *g* is constant while it tapers in width toward its outer end, causing the convexly curved faces to diminish in width and the flat side faces to increase in width as the outer end of the tine is approached, as shown in Fig. 1.

I claim:

The ornamental design for a fork, or analogous article, as shown and described.

HENRY CHARLES QUINCY.

Correction in Design Letters Patent No.
44,112.

It is hereby certified that in Letters Patent No. 44,112, granted May 27, 1913, upon the application of Henry Charles Quincy, of Newburyport, Massachusetts, for a Design for a Fork or Analogous Article," an error appears in the printed specification requiring correction as follows: Line 15, for the numerals "42,633" read 42,663; and that the said Letters Patent should be read with this correction therein that the same may conform to the record of the case in the Patent Office.

Signed and sealed this 24th day of November, A. D., 1914.

[SEAL.]

R. F. WHITEHEAD,

Acting Commissioner of Patents.
